Inventor,

David B. Saltsman
By Fred L. Chappell
Att'y.

UNITED STATES PATENT OFFICE.

DAVID B. SALTSMAN, OF DOWAGIAC, MICHIGAN, ASSIGNOR TO DOWAGIAC MANUFACTURING COMPANY, OF DOWAGIAC, MICHIGAN.

GRAIN-DRILL.

SPECIFICATION forming part of Letters Patent No. 737,152, dated August 25, 1903.

Application filed April 16, 1903. Serial No. 152,921. (No model.)

To all whom it may concern:

Be it known that I, DAVID B. SALTSMAN, a citizen of the United States, residing at the city of Dowagiac, in the county of Cass and State of Michigan, have invented certain new and useful Improvements in Grain-Drills, of which the following is a specification.

This invention relates to improvements in grain-drills.

10 It relates particularly to improvements in disk furrow-openers for grain-drills, although the structure is adapted for use in other relations.

The objects of this invention are, first, to provide an improved disk furrow-opener which is simple and compact in its structure; second, to provide an improved disk furrow-opener in which the bearings are so arranged that the strain thereon and the consequent 20 wear are reduced to a minimum.

Further objects and objects relating to structural details will definitely appear in the detailed description to follow.

I accomplish the objects of my invention 25 by the devices and means described in the following specification.

The invention is clearly defined, and pointed out in the claims.

A structure embodying the features of my 30 invention is clearly illustrated in the accompanying drawings, forming a part of this specification, in which—

Figure 1 is a detail side elevation view of a structure embodying the features of my invention. Fig. 2 is an enlarged detail sectional view taken on a line corresponding to line 2 2 of Fig. 1. Fig. 3 is an enlarged detail side elevation view of the boot, showing the arrangement thereof for supporting the 40 disks.

In the drawings the sectional views are taken looking in the direction of the little arrows at the ends of the section-lines, and similar letters of reference refer to similar parts 45 throughout the several views.

Referring to the lettered parts of the drawings, the boot A is of the usual or any desired construction and is provided with a bracket, to which the draw-bar A" is attached.

50 Toward the lower end of the boot is a bracket or projection A', which is adapted to receive

the bearing-blocks C, which are secured thereto by a bolt D. The bearing-blocks are provided with an annular flange or disk-like head c.

55

The disks B are provided with a central opening and are mounted upon the bearing-blocks C, contacting with the inner face thereof. Secured to the outer faces of the disks B are bearing-plates B', which are adapted to fit over the annular flange or disk-like head c of the bearing-blocks. The bearing-plates B' are provided with threaded openings to receive the threaded dust-caps b, so that the bearing is thoroughly protected. Oil 65 may be introduced into the bearings in any convenient or usual manner, the means not being here illustrated. By this arrangement of the parts a very compact bearing is produced and the disks are supported in a manner that the strain thereon is reduced to a minimum. The bearing is thoroughly protected from dirt and dust and is very durable. It is simple and economical to produce and 70 convenient to assemble. The bearing-surface 75 is comparatively wide and the bearing thin, so that there is no undue strain upon the disks.

Although I have illustrated and described my invention as adapted to furrow-openers 80 for grain-drills, it is evident that it is adapted for use in other relations. I have illustrated and described the same in the form preferred by me on account of its simplicity and durability. I am aware, however, that it is capable of considerable structural variation without departing from my invention.

Having thus described my invention, what I claim as new, and desire to secure by Letters Patent, is—

90

1. The combination of a boot; bearing-blocks C having disk-like heads c secured thereto; furrow-opening disks B embracing said bearing-blocks; bearing-plates B' secured to said disks and embracing said flanges; and dust-caps threaded to engage said bearing-plates, all coacting for the purpose specified.

2. The combination of a boot; a bearing-block having a disk-like head on its outer ends secured thereto; a furrow-opening disk on said bearing-block; a bearing-plate em-

bracing said bearing-head secured to said disk; and dust-caps secured to said bearing-plates.

3. The combination of a boot; a bearing-block having a disk-like head on its outer ends secured thereto; a furrow-opening disk on said bearing-block; a bearing-plate embracing said bearing-head secured to said disk.

10 4. A bearing-block having a disk-like head

on its outer end; a disk embracing said bearing-block; and a bearing-plate embracing said head secured to said disk.

In witness whereof I have hereunto set my hand and seal in the presence of two witnesses.

DAVID B. SALTSMAN. [L. S.]
